UNITED STATES PATENT OFFICE.

AUGUSTA DULL, OF LOS ANGELES, CALIFORNIA.

STREET INDICATOR.

Application filed July 18, 1923. Serial No. 652,279.

To all whom it may concern:

Be it known that I, AUGUSTA DULL, a citizen of the United States, residing at Los Angeles, in the county of Los Angeles and 5 State of California, have invented new and useful Improvements in Street Indicators, of which the following is a specification.

This invention relates to street and station indicators for passenger vehicles, and 10 more particularly for railway vehicles.

An object of the invention is to provide a station or street indicator of extremely simple and practicable construction and involving a single motor constantly in mesh with 15 one of a set of constantly meshed gears, whereby to drive either of selective winding reels. Another object is to provide an improved and manually controlled, electrically actuated clutch means for selectively 20 connecting one or the other of the reels to the constantly running gears.

An object is to provide an electrically operated street indicator including safety electric means to prevent the overrunning 25 of the ribbon on which the street or station names are provided. Another object is to provide an apparatus including momentary contact switches for initiating operation of the motor and to provide means for automatically 30 breaking the circuit of the motor after the setting of each station or street signal. An object is to provide means operative to automatically break the motor circuit and to maintain a broken motor circuit 35 to prevent the sign ribbon from being overrun by inadvertence, and an object is to provide manual means for opening the circuit of the means which breaks the motor circuit.

40 Other objects and advantages will be made manifest in the following specification of an embodiment of the invention illustrated in the accompanying drawings, wherein:

45 Figure 1 is a perspective of the preferred form of indicator.

Fig. 2 is a longitudinal section between the top and bottom of the shell of the indicator and showing parts in plan.

50 Fig. 3 is a detail sectional view of the clutch mechanism of one of the reels.

Fig. 4 is a perspective of a portion of the indicator tape.

Fig. 5 is a sectional and diagrammatic view of the apparatus, including the shell. 55

Fig. 6 is a plan showing diagrammatically the position of the indicator in a car.

The apparatus, as shown, includes mechanism preferably arranged within a shell 2 of suitable dimensions and which has convergent front windows 3 and 3^a so that when the back of the shell is secured as shown in Figure 6 to a side wall of a car, then the occupants can see one or the other of the windows 3 or 3^a, through which may be observed the displayed street or station name 5, Figures 1 and 4. The station or street names are provided at suitable intervals on a flexible ribbon or tape 10, and between street or station names or indexes there is provided in the tape apertures 11, the final aperture 11^a at each end of the tape being of greater length than the remainder for a purpose to be described. 65

The tape is adapted to be readily attached 75 at each of its ends to a spool or reel 12, two of which are provided, and these are adapted to be readily attached to and detached from spindles 13; the reels being keyed or pinned as at 14 to be rotated with and by the spindles, which are supported in a suitable bearing or frame 15 mounted in the shell 2.

The spindles are provided with shoulders 16, preventing their downward axial movement, and above these are springs 17, reacting against clutch hubs 18, having discs 19 at their upper ends. These discs form clutch members to selectively lock with constantly meshed gears 20, which are provided with pinholes 20^a, Figure 3, to receive clutch or locking pins 21 on the respective discs 19. 85

The clutch hubs 18 are loosely mounted 90 on the spindles 13 and are positively connected to the gears for rotation therewith by connecting pins 22 fixed in the gears and 95 slidably in apertures 23 in the clutch discs 19. The gears 20 are loosely mounted on reduced end portions of the spindles 13 and above the gears are rigidly secured on the spindles clutch discs 24, which are provided with apertures 24^a disposed so as to register with and receive the clutch pins 21. 100

when the clutch discs 19 are respectively permitted to be shifted upwardly by their springs 17. When the clutch pins 21 are in interlocking engagement with the clutch discs 24, it will be seen that the spindles may be rotated by and with the gears 20.

Means for driving the gears is shown as including an irreversible motor 25 mounted in the shell 2 and having on its shaft a pinion 26 engaging with one of the gears 20. The gears are in constant mesh with each other and therefor rotate in opposite directions.

As shown in Figure 2, a signal tape 10 passes tangentially and in opposite directions from the reels 12, which have parallel axes, and outwardly toward idler drums 27, arranged with axes parallel in a common plane, and from the outer faces of which the tape passes outwardly toward a central guide drum 28, arranged at the front apex of the shell so that convergent stretches of the indicator tape 10 are exposed at the windows 3 and 3^a by that portion of the tape extending convergently forwardly from the end drums.

It will be seen that in using an indicator with a plurality of windows for simultaneously displaying similar station or street names, the tape 10 will be provided with a number of each station or street name corresponding to the number of windows through which the station or street will be indicated. Obviously, in some cases only a single window may be employed, and in such cases there would be but a single occurrence of each station or street name on the tape. As shown in Figure 4, the street names are in each case duplicated, and between each pair of identic street names occurs the aperture 11 before mentioned.

The motor 25 is adapted to be intermittently energized by the motorman, conductor, guard or other authorized person, at a suitable moment so as to set the station or street indicator in ample time before the arrival of the vehicle at the next street or station. For this purpose, to the motor is connected a conductor 25^a, which is connected to an armature 25^b engaging a contact 30 connected by a line 30^a to a service or main line 31 from a source of current. The motor circuit includes a line 32 connected at 33 to the parallel main circuit line 34. Thus, when the switch-forming armature 25^b is in engagement with the contact 30, the motor is energized and will drive the gears 20, one of which will be clutched or coupled to its contiguous shaft disc 24 and the latter will be driven. The motor switch armature 25^b is connected to a spring 25^c holding it either open or closed.

The motor switch armature 25^b is adapted to be closed by a manually controlled means

including an electromagnet 35 connected at 35^a to the main feed wire 31, and it is also connected by a wire 35^b to a line 36 having terminals 37-37' forming a part of respective momentary contact switch structures 38-38', from which extend conductors 40-40^a connected respectively to electromagnets 41-41^a. These magnets are connected by wire 42 to the main circuit conductor 34. Thus, if either momentary contact switch 38 or 38' be closed, current flows through the main line 31 to the switch magnet 35, thence through wire 35^b to one end or the other of the wire 36 and through the closed switch 38 or 38' and thence to its respective magnet 41 or 41^a and thence by wire 42 to the main circuit conductor 34. This results in energizing the motor switch magnet 35 and closing the motor switch member 25^b against its contact 30 so that the motor will be energized and the gears driven.

The electromagnets 41-41^a are in the form of solenoids having cores 43-43^a, the upper ends of which are connected to a lever device 44, centrally fulcrumed on a bearing 45 forming a part of the frame 15. The lever device 44 is provided as means for positively disconnecting a clutch member 19 which may be coupled to its respective spindle disc 24.

The clutch hubs 18 are provided with shoulders 18^a, Figure 3, on which ride pins 46 provided on the lever 44, so that when the solenoid is energized, the downwardly moving portion of the lever will, through its pins 46, shift the respective clutch member 18 down and thus disengage the respective spindle disc 24, so that while the gears and clutch members may be concurrently operating, one of the spindles will be disengaged.

Substantially concurrently with the disengagement of one clutch device, the other clutch device will be shifted into effective position by its respective spring 17 surrounding a spindle 13. The connecting spring 17 thrusts the clutch pin 21 up against the bottom face of the respective spindle disc 24 and as soon as the aperture 24^a therein registers with the clutch pin 21, these parts become coupled and the respective spindle 13 and its reel 12 will be driven.

Since the reels are fixed on the spindles 13, and since the clutch members 18 are loose on the spindles and are selectively coupled thereto, it will be seen that the spindle which is coupled to its driving clutch will operate to wind the tape 10 on one reel, while the opposite reel will be free as to its respective clutch and may, therefore, unwind, irrespective of the fact that its respective gear 20 and clutch device 18 are being rotated.

When the operator presses a momentary contact switch 38 or 38', the motor circuit

is closed and the motor will be started and continue to run until its circuit is automatically broken so as to shift the indicating tape so as to successively present the street

5 or station names at the window or windows, as the case may be. As soon as the name is properly registered with the windows, the motor circuit is automatically broken in the following manner:

10 The motor wire 32 is provided with a branch line 32^a grounded to one of the idlers 27, and at the line of the apertures 11 in the tape 10 there is provided a contact roller 32^b from which extends a wire 32^c leading to a 15 normally closed switch 47. The circuit closing switch 47 is connected by a line 48 to another normally closed switch 47^a, which in turn is connected by a wire 49 to an electromagnet 50, which is connected by a wire 51 20 to the motor circuit wire 25^a. Therefore, when the operator has closed either of the master switches 38—38', the motor will be started and will run until one of the tape apertures 11 runs under the contact roller 32^b which, upon engaging the idler drum 27, 25 will short the motor circuit through the line 32^a, line 32^c to the closed switches 47—47^a and line 48, thence by wire 49 to the electromagnet 50, thence by wire 51 to the line 25^a; 30 whereupon the energized magnet 50 will attract the switch member 25^b and thus break the motor circuit at the contact 30. The switch member 25^b will be held in circuit-breaking or open position by its spring device 25^c.

35 The momentum of the running parts will be sufficient to carry the tape 10 a sufficient degree to shift each of the short apertures 11 beyond the short-circuiting contact device 32^b so that when the operator next closes either of the master switches 38 or 38', the parts will be in such condition as to permit the closing of the motor circuit when the magnet 35 is energized and its armature 25^b 40 drawn over to close the motor circuit at contact 30. It is obvious that as the tape 10 is shifted, the circuit closing roller 32 is disengaged from the drum 27 and the motor circuit-breaking magnet 50 is therefore deenergized.

45 It is desirable to provide for the automatic locking of the clutch disengaging lever 44 in either of its two normal positions so that at the end of a run of the vehicle, when the operator desires to selectively determine the direction of movement of the tape 10, this is 50 accomplished by the initial action of the mechanism by closure of either of the switches 38 or 38', and thereafter the selected clutch is adapted to remain in locked position until subsequently disengaged. The locking means is shown as including a 55 spring actuated latch 55 for each end of the lever 44, the latches being provided with

armature parts 55^a disposed adjacent to the 65 core poles 56 provided on and by the solenoids 41.

70 As above described, the master switches are connected so as to substantially concurrently energize the motor starting magnet 35 and the respective solenoids 41—41^a. Therefore, as the motor circuit is closed initially at each end of a run to commence a winding of the tape, on one reel or the other, the clutch actuating lever 44 will be 75 shifted by the energized solenoid and the upwardly latched end of the clutch member 44 will be released by the tripping of its latch 55 by the energized solenoid, while the opposite and upwardly moving end of 80 the lever 44 will be latched in its upper position by its respective latch member 55.

85 The shorter apertures 11 provide for the interruption of the motor circuit as soon as the necessary shift of the tape has been completed by the motor and, as stated, momentum of the parts will shift the apertures 11 to disengage the short circuiting member 32^b from the grounded drum 27. Therefore, 90 as soon as the operator again actuates a momentary contact master switch, the motor will be again energized.

95 To prevent the operator's overrunning the tape after passing of the last station name on the tape, this latter is provided with an elongated aperture 11^a at each end, and this aperture is designed to permit closure at the contact device 32^b on the drum 27 and prevent operation of the motor by closure of the master switches, or either of 100 them, until the operator opens one or the other of the closed switches 47—47^a. The terminal apertures 11^a are of such length as not to be carried from the short-circuiting device 32^b by momentum of the parts. 105

110 There is a pair of switches 38—47 and 38'—47^a at each end of the vehicle, and these switches of each pair are arranged, for purposes of preventing accidental or inadvertent closure, at such distance from each other that the operator must make intentional movement to concurrently actuate the switches 38—47 or 38'—47^a. If the operator closes a switch 38 or 38' while a tape aperture 11^a permits short-circuiting 115 at the contact device 32^b, it will only serve to attract the switch armature 25^b and this will be instantly retracted by the magnet 50. In order to break the closed circuit through the magnet 50, the operator must open the 120 switch 47 or the switch 47^a, according to which end of the vehicle he may be positioned. By opening either switch 47 or 47^a and then closing the master switch 38 or 38', the short circuit at the device 32^b is overcome 125 and the motor, being therefore energized by closure of its switch 25^b, will start the action of the driving gears 20

and the rewinding of the tape will be initiated. The lever actuated solenoids 41—41^a are controlled by the respective switches 38—38' from opposite ends of the vehicle, so as to wind and rewind the tape according to the direction of travel.

It is to be noted that the circuit as here described eliminates circuit-breaking at and on the contact roller or drum 27 and therefore prevents destruction of the ribbon passing under the same, since the circuit current is broken by the opening of the motor switch 25^b.

The circuit opening switches 47—47^a may be held open until, by successive operation of the master switches 38—38', the motor can be substantially continuously run for winding up the entire tape 10, where it is desirable to make changes or replace tape rolls.

If a mistake is made in the operation of the switches, as by successive pressure, the tape can be re-set by simply operating the control switches at the opposite end of the vehicle to sufficiently reverse the wind of the tape to overcome the error.

Further embodiments, modifications and variations may be resorted to within the principle of the invention.

30 What is claimed is:

1. A street or station indicator comprising, in combination, a pair of winding reels, parallel spindles to which the reels are detachably connected, an intermittently operative motor, a pair of meshed gears one of which is engaged and driven by said motor, and clutch means for selectively operatively connecting the spindles to the gears.

2. A street or station indicator comprising, in combination, a pair of winding reels, parallel spindles to which the reels are detachably connected, an intermittently operative motor, a pair of meshed gears one of which is engaged and driven by said motor, clutch means for selectively operatively connecting the spindles to the gears, and means for controlling the engaging and disengaging action of the clutch means as to the respective spindles.

50 3. A street or station indicator comprising, in combination, a pair of winding reels, parallel spindles to which the reels are detachably connected, an intermittently operative motor, a pair of meshed gears one of which is engaged and driven by said motor, and clutch means for selectively operatively connecting the spindles to the gears, said clutch means including members fixed to the spindles and elements loosely and slidably mounted on the spindles to be coupled to the said members.

60 4. A street or station indicator comprising, in combination, a pair of winding reels, parallel spindles to which the reels are detachably connected, an intermittently op-

erative motor, a pair of meshed gears one of which is engaged and driven by said motor, and clutch means for selectively operatively connecting the spindles to the gears, said clutch means including elements 70 slidably and rotatably mounted on the spindles and operatively attached to the gears to rotate therewith, and clutch members secured on the spindles and engageable by parts on said elements to be driven thereby.

5. A street or station indicator comprising, in combination, a pair of winding reels, parallel spindles to which the reels are detachably connected, an intermittently operative motor, a pair of meshed gears one of which is engaged and driven by said motor, and clutch means for selectively operatively connecting the spindles to the gears, said clutch means including elements 80 slidably and rotatably mounted on the spindles and operatively attached to the gears to rotate therewith, and clutch members secured on the spindles and engageable by parts on said elements to be driven thereby, 85 said slideable clutch elements being yieldingly thrust in one direction.

6. A street or station indicator comprising, in combination, a pair of winding reels, parallel spindles to which the reels are detachably connected, an intermittently operative motor, a pair of meshed gears one of which is engaged and driven by said motor, and clutch means for selectively operatively connecting the spindles to the gears, said clutch means including elements 90 slidably and rotatably mounted on the spindles and operatively attached to the gears to rotate therewith, and clutch members secured on the spindles and engageable by parts on said elements to be driven thereby, 95 said slideable clutch elements being yieldingly thrust in one direction.

7. A street or station indicator comprising, in combination, an intermittently operative motor, a pair of meshed gears one of which is driven directly by the motor, reel carrying spindles on which the said gears are loosely mounted, said gears being provided each with a pinhole, clutch discs fixed on the spindles and each having a pinhole, 100 and clutch elements rotatably and shiftably mounted on said spindles and being provided with pins to pass through the pinholes of the gears and into the pinholes of the clutch discs whereby to operatively connect the gears to the spindles to drive the 105 same.

8. A street or station indicator comprising, in combination, an intermittently operative motor, a pair of meshed gears one of which is driven directly by the motor, reel 110 carrying spindles on which the said gears are loosely mounted, said gears being provided each with a pinhole, clutch discs fixed on the spindles and each having a pinhole, 115 and clutch elements rotatably and shiftably mounted on said spindles and being provided with pins to pass through the pinholes of the gears and into the pinholes of the clutch discs whereby to operatively connect the gears to the spindles to drive the 120 same.

130

- carrying spindles on which the said gears are loosely mounted, said gears being provided each with a pinhole, clutch discs fixed on the spindles and each having a pinhole, and clutch elements rotatably and shiftably mounted on said spindles and being provided with pins to pass through the pinholes of the gears and into the pinholes of the clutch discs whereby to operatively connect the gears to the spindles to drive the same, and means for yieldingly thrusting the clutch elements to the effective clutching position and operative to hold the clutch pins against contiguous faces of the clutch discs until the pinholes therein register with the clutch pins. 10
9. A street or station indicator comprising, in combination, an intermittently operative motor, a pair of meshed gears one of which is driven directly by the motor, reel carrying spindles on which the said gears are loosely mounted, said gears being provided each with a pinhole, clutch discs fixed on the spindles and each having a pinhole, clutch elements rotatably and shiftably mounted on said spindles and being provided with pins to pass through the pinholes of the gears and into the pinholes of the clutch discs whereby to operatively connect the gears to the spindles to drive the same, and means for controlling concurrent movement of the clutch elements in opposite directions from and to effective clutching positions. 20
- 30 10. A street or station indicator comprising, in combination, an intermittently operative motor, a pair of meshed gears one of which is driven directly by the motor, reel carrying spindles on which the said gears are loosely mounted, said gears being provided each with a pinhole, clutch discs fixed on the spindles and each having a pinhole, clutch elements rotatably and shiftably mounted on said spindles and being provided with pins to pass through the pinholes of the gears and into the pinholes of the clutch discs whereby to operatively connect the gears to the spindles to drive the same, and means for controlling concurrent movement of the clutch elements in opposite directions from and to effective clutching positions, said means including a lever combined with said clutch elements. 40
- 50 11. A street or station indicator comprising, in combination, an intermittently operative motor, a pair of meshed gears one of which is driven directly by the motor, reel carrying spindles on which the said gears are loosely mounted, said gears being provided each with a pinhole, clutch discs fixed on the spindles and each having a pinhole, clutch elements rotatably and shiftably mounted on said spindles and being provided with pins to pass through the pinholes of the gears and into the pinholes of the clutch discs whereby to operatively connect the gears to the spindles to drive the same, and means for locking the last named means in each of its two normal positions. 50
12. A street or station indicator comprising, in combination, a pair of parallel spindles and tape winding reels mounted on the spindles, a motor, a pair of meshed gears one of which is directly driven by said motor, said gears being loosely mounted on said spindles, and clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel. 60
- 70 13. A street or station indicator comprising, in combination, a pair of parallel spindles and tape winding reels mounted on the spindles, a motor, a pair of meshed gears one of which is directly driven by said motor, said gears being loosely mounted on said spindles, clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, and manually controlled means for effecting intermittent operation of the motor. 80
- 80 14. A street or station indicator comprising, in combination, a pair of parallel spindles and tape winding reels mounted on the spindles, a motor, a pair of meshed gears one of which is directly driven by said motor, said gears being loosely mounted on said spindles, clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, and manually controlled means for effecting a reversal of the effective clutch actions on the spindles whereby to reverse the winding direction of travel of the said tape by the reels. 90
- 90 15. A street or station indicator comprising, in combination, a pair of parallel spindles and tape winding reels mounted on the spindles, a motor, a pair of meshed gears one of which is directly driven by said motor, said gears being loosely mounted on said spindles, and clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, and manually controlled means for effecting a reversal of the effective clutch actions on the spindles whereby to reverse the winding direction of travel of the said tape by the reels. 100
- 100 16. A street or station indicator comprising, in combination, a pair of parallel spindles and tape winding reels mounted on the spindles, a motor, a pair of meshed gears one of which is directly driven by said motor, said gears being loosely mounted on said spindles, and clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, and manually controlled means for effecting a reversal of the effective clutch actions on the spindles whereby to reverse the winding direction of travel of the said tape by the reels. 110
- 110 17. A street or station indicator comprising, in combination, a pair of parallel spindles and tape winding reels mounted on the spindles, a motor, a pair of meshed gears one of which is directly driven by said motor, said gears being loosely mounted on said spindles, and clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, and manually controlled means for effecting a reversal of the effective clutch actions on the spindles whereby to reverse the winding direction of travel of the said tape by the reels. 120
- 120 18. A street or station indicator comprising, in combination, a pair of parallel spindles and tape winding reels mounted on the spindles, a motor, a pair of meshed gears one of which is directly driven by said motor, said gears being loosely mounted on said spindles, and clutch means including parts concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, and manually controlled means for effecting a reversal of the effective clutch actions on the spindles whereby to reverse the winding direction of travel of the said tape by the reels. 130

concurrently movable in opposite directions, whereby to connect and disconnect the gears respectively to and from the spindles so that one spindle will be driven by the operating gears to wind a tape on its reel whilst the other spindle will be released to rotate freely with and by the unwinding of the tape from its reel, said gears operating to

drive the spindles in opposite directions whereby to effect a reversal of direction of travel of the tape by the reels when the clutches are intermittently reversed in effectiveness.

In testimony whereof I have signed my name to this specification.

AUGUSTA DULL.
